[57] CLAIM

The ornamental design for a can compactor, as shown and described.

DESCRIPTION

FIG. 1 is a perspective view of a can compactor of the present invention;

FIG. 2 is a left side elevational view of the can compactor;

FIG. 3 is a right side elevational view of the can compactor;

FIG. 4 is a top plan view of the can compactor;

FIG. 5 is a bottom plan view of the can compactor;

FIG. 6 is a front elevational view of the can compactor; and,

FIG. 7 is a rear elevational view of the can compactor.

The broken line showing is for illustrative purposes only and forms no part of the claimed design.
